CLAIM

The ornamental design for a spray cap for an aerosol container, as shown and described.

DESCRIPTION

FIG. 1 is a rear perspective view of a spray cap according to the present invention;

FIG. 2 is an elevation view of the front thereof;

FIG. 3 is an elevation view of the rear thereof;

FIG. 4 is an elevation view of a side thereof, the opposite side being a mirror image thereof;

FIG. 5 is a plan view of the top thereof;

FIG. 6 is a rear perspective view of a spray cap of the present invention shown in its environment of use;

FIG. 7 is an elevation view of the front thereof, shown in its environment of use;

FIG. 8 is an elevation view of the rear thereof, shown in its environment of use;

FIG. 9 is an elevation view of a side thereof, shown in its environment of use; and,

FIG. 10 is a plan view of the top thereof, shown in its environment of use.

The broken line showing of the aerosol can in FIGS. 6-10 is included for the purpose of illustrating environment and forms no part of the claimed design.
